ROCKER SHAFT BEARING FOR LOOMS

Walter R. Stone, Inman, S. C.

Application November 27, 1934, Serial No. 755,023

2 Claims. (Cl. 308—21)

This invention relates to a bearing for the rocker shaft for looms and more especially to a bearing which can be adjusted without disrupting any of the parts of the loom and without the necessity of dismantling any portion of the loom to take up wear in the rocker shaft bearing.

In a loom, the rocker shaft penetrates the frame of the loom and has a bearing on each end thereof. Immediately inside the loom frame the sword is usually secured to the rocker shaft and immediately outside the loom frame the foot for the shoe of the picker stick is usually secured, leaving no additional room for the insertion of additional bearings and the like. I have provided a new type of bearing which takes up no more space than the conventional bearing and loom frame and which can be adjusted very easily without the necessity of dismantling any portion of the loom.

It is therefore an object of this invention to provide a bearing for rocker shafts of looms which can be adjusted to compensate for wear without the necessity of dismantling any portion of the loom.

Some of the objects of the invention having been stated, other objects will appear as the description proceeds when taken in connection with the accompanying drawing, in which:—

Figure 1 is an isometric view of the lower portion of a loom frame showing my invention applied thereto;

Figure 2 is a sectional view taken along the line 2—2 in Figure 1 and immediately outside the loom frame;

Figure 3 is a transverse sectional view taken along line 3—3 in Figure 2;

Figure 4 is an inverted isometric view of the portion of the bearing appearing on the outside of the loom frame;

Figure 5 is an isometric view of the portion of the bearing which is secured on the inside of the loom frame to cooperate with the portion of the bearing shown in Figure 4.

In the drawing, the numeral 10 indicates the portion of the loom frame in which the rocker shaft is mounted. This loom frame usually has a bearing secured on the outside thereof which projects through a suitable hole in the loom frame and in which the rocker shaft 12 of the loom is usually mounted. This bearing is similar to the bearing in Figure 4 except that it does not have any cutaway portion, but is a plain member secured to the exterior of the loom with a barrel portion forming a bearing

for the rocker shaft. This soon becomes worn and in order to replace it with a new bearing, it is necessary to remove the foot from the end of the rocker shaft and insert a new bearing, which is costly.

By my improved structure, the bearing can be adjusted from time to time, to take up a small amount of wear and therefore the bearing will not become badly worn and thus turn out an inferior product before the new bearing is installed, therefore, adjustments can be made from week to week to keep the loom in first class condition to compensate for wear as it occurs.

My invention therefore, contemplates a bearing comprising the portion 13 having holes 14 and 15 therein, and a semi-circular bearing portion 16, the portion 13 being cut away as at 17. This is placed on the outside of the loom frame by means of suitable bolts 18 and 19 penetrating the holes 14 and 15 and also penetrating holes in the loom frame. The member 13 also has pins 20 and 21 which fit into holes in the loom frame to better secure the same in position. The member 13 and associated parts are placed on the loom in an inverted position from that shown in Figure 4, and therefore the bottom portion of the bearing 16 is open. I then place a member 23 on the inside of the loom with the rocker shaft 12 inserted through an opening 24, said member 23 having slots 25 and 26 which are penetrated by bolts 18 and 19 and suitable nuts 27 and 28 are placed on said bolts, therefore, the parts 13 and 23 are firmly secured to the loom frame 10. This member 23 has a portion 29 which has an arcuate face 30 on which the rocker shaft 12 is adapted to rest. The upper end of member 23 has a lip 31 having a threaded hole 32 therein in which a set screw 33 is secured. It is seen that by loosening the bolts 18 and 19 and tightening up on the set screw 33, the amount of wear between the rocker shaft 12 and the bearing portions 16 and 29 can be taken up to a snug fit. When the bolts 18 and 19 are loosened during this tightening operation, the bearing cannot be tightened to a greater extent than is necessary to compensate for wear since bearing 13 is held stationary by means of pins 20 and 21.

The sword 34 is usually secured on the rocker shaft 12 immediately inside the inner surface of member 23.

Bearing portion 16 also has an oil hole 35 therein to facilitate lubrication in addition to oil hole 36, which is also therein. The conventional foot 37 is secured outside the loom frame

on the rocker shaft, and thus it is seen that I have provided a bearing which occupies no more space than former bearings and which can be easily adjusted to compensate for wearing.

5 The foot 37 has an outwardly extending foot portion on which conventional shoe 43 is adapted to have rocking movement. A picker stick 42 has its lower end secured in said foot. A conventional spring housing 40 is disposed on the 10 lower side of the extension of foot 39 and a strap 41 has one end secured to said housing and its other end is secured to picker stick 42. Parts 15 37, 40, 41, 42 and 43 are conventional.

In the drawing and specification there has 20 been set forth a preferred embodiment of the invention, and although specific terms are employed, they are used in a generic and descriptive sense only, and not for purposes of limitation, the scope of the invention being set forth in the appended claims.

I claim:

1. A bearing for rocker shafts for looms comprising in combination, a loom frame member having an opening therein, a bearing member 25 secured to the outer surface of the frame of the loom and having an arcuate bearing portion projecting into said opening and encircling the upper portion of the rocker shaft, a second bearing member secured to the inner surface of the 30 frame of the loom and having an arcuate bearing portion projecting into said opening and engaging the lower surface of the rocker shaft immediately below the arcuate portion on said first bearing member, a centrally disposed lip 35 on the upper end of the second bearing member projecting laterally over the upper edge of the loom frame member, a set screw threadably mounted in said lip and having its lower end in engagement with the loom frame, both of

said bearing members having coinciding slots 5 therein, a pair of bolts penetrating said slots in both of said bearing members and the loom frame, said bolts when loosened permitting movement of the set screw to move the second bearing member upwardly to take up wear between the bearing portions and the rocker shaft.

2. In a loom having a frame provided with an opening which is penetrated by a rocker shaft, a bearing for said shaft comprising a plate disposed against the inner surface of the loom frame and having an opening therein much larger than the shaft and through which the shaft is adapted to pass, a pair of vertically disposed slots in said plate, bolts mounted in said 15 slots and penetrating the loom frame for securing the plate to the loom frame, a laterally projecting lip on the upper portion of the plate adapted to extend over the upper edge of the frame, a set screw mounted in said lip and having its lower end adapted to engage the loom frame for adjusting said plate vertically with relation to the frame, and arcuate bearing portion projecting from said plate through the opening in the frame and serving to support the 25 shaft for rotation, a second plate having a pair of holes therein and disposed on the outside of the frame and having said bolts penetrating the holes therein, said second plate having an extension projecting into the opening in said 30 frame and above said shaft, said extension having an arcuate bearing surface on its lower side for engaging said shaft, said second plate being cut away centrally thereof to permit the second plate to be secured in position with relation to 35 said shaft without passing the same over the end of the shaft.
